DESIGN FOR A DOOR CHECK LOCK

Franklin J. Petzke, Minneapolis, Minn.

Application October 15, 1943, Serial No. 111,372

Term of patent 14 years

To all whom it may concern:

Be it known that I, Franklin J. Petzke, a citizen of the United States, residing at Minneapolis, in the county of Hennepin and State of Minnesota, have invented a new, original, and ornamental Design for a Door Check Lock, of which the following is a specification, reference being had to the accompanying drawing, forming part thereof.

Figure 1 is a perspective view of the door check lock, showing my new design;

Figure 2 is a top plan view;
Figure 3 is a side elevational view;
Figure 4 is an elevational view taken from the opposite side;
Figure 5 is an end elevational view; and
Figure 6 is an elevational view taken from the opposite end thereof.

I claim:
The ornamental design for a door check lock, as shown.

FRANKLIN J. PETZKE.
